JOSEPH C. COFFEE, OF WILKES-BARRE, PENNSYLVANIA, ASSIGNOR TO WALES ADDING MACHINE COMPANY, OF WILKES-BARRE, PENNSYLVANIA, A CORPORATION OF PENNSYLVANIA.

SIGN-PRINTING MECHANISM.

Application filed May 13, 1921. Serial No. 469,135.

To all whom it may concern:

Be it known that I, JOSEPH C. COFFEE, a citizen of the United States, residing at Wilkes-Barre, Luzerne County, Pennsylvania, have invented new and useful Improvements in Sign-Printing Mechanisms, of which the following is a specification.

Heretofore, it has been customary in calculating machines, to provide means to characterize non-add, total and sub-total operations of the machine, by the imprint of appropriate designating signs on the work sheet.

The sign types are mounted in a typecarrier which is adjustable relatively to the printing line to bring the appropriate sign to printing position depending upon the particular special mechanism set for operation.

26 The term "special" is used to indicate mechanisms, other than numeral key mechanisms, which, when set, affect, alter or change the customary operation of the machine in adding and printing amounts set up by depressing the usual numeral keys.

30 A sign printing hammer similar to the regular denominational printing hammers of the calculating machine, effects the impression of the special signs, the sign printing hammer being set or cocked by the customary universal hammer-resetting means, and held in set or cocked position thereby, and by the usual universal hammer detent, as well as by an individual dog.

35 In general, one of the special sign types, as the non-add sign type, for instance, normally remains at the printing line, so that it is only necessary to provide means controlled by the non-add mechanism, to effect 40 non-accumulation on the counters, and to displace the individual dog which normally locks the sign printing hammer against operation when the universal detent is released at each machine operation.

45 The remaining special controlling mechanisms, besides variously affecting the usual operation of the machine, and tripping the individual sign printing hammer dog, must also operate to shift the special sign typecarrier to bring the appropriate sign type to the printing line.

Naturally, assuming that the uppermost sign type is the one normally at the print-

ing line, the typecarrier must be shifted progressively increasing distances to bring 55 the successive types below the uppermost type, to the printing line. Heretofore, the means which trips the individual dog for the sign printing hammer has been shifted by the special mechanisms which shift the sign 60 typecarrier, through substantially the same distance that the sign printing typecarrier is shifted, and displaced the dog when the sign type-carrier was shifted one step as well as when the carrier was shifted a 65 greater number of steps.

In adding an extra sign type, as a non-print sign, to the number of sign types mounted in the typecarrier, it is obviously necessary for the non-print mechanism to 70 actuate the sign typecarrier a step farther than heretofore, in order to bring such additional sign to the printing line.

Furthermore, the total and sub-total mechanisms in the Wales machine are so arranged that if an operator accidentally or intentionally depresses either of the total or sub-total keys partway only, the machine will either be locked against operation, or, if operable, will either reset the keys to their 80 idle positions, or shift them to their effective positions.

Therefore, there is no liability of printing a non-add sign, for instance, opposite a total or sub-total amount, nor can a total 85 sign be printed alongside a sub-total amount or vice versa.

But there is no such safety device applied to the non-print key-controlled mechanism which, like the total and sub-total keys, 90 must set the non-print mechanism, position the sign typecarrier to bring the non-print sign to the printing line, and trip the individual locking dog to free the sign printing hammer.

One object of the present invention is to insure that the non-print or other sign will be properly positioned at the printing line to appropriately designate the non-print or other operation, and to prevent the operator 100 from intentionally or accidentally manipulating the special keys which control the special functions of the machine and the printing of designating signs, to effect the printing of an inappropriate sign to designate an idle operation or an operation other

than that which the mechanism controlled by the manipulated key is intended to accomplish.

To these and other ends, my invention includes several novel features and combinations, all of which will be more fully disclosed hereinafter and particularly pointed out in the claims.

In the accompanying drawings, Fig. 1 is a longitudinal sectional view through a Wales machine; parts being omitted for the sake of clearness.

Fig. 2 is a detail sectional view of a portion of the printing mechanism of the Wales machine, showing the special sign printing mechanism, with my improvements in the non-print key control thereof, the mechanism being in its normal idle position; and

Fig. 3 is a similar view, showing the positions of the parts when the non-print key has been depressed, the sign printing hammer being in discharged position, at the end of the forward stroke of the machine.

I have elected to show one embodiment of my invention applied to the Wales calculating machine, examples of which are illustrated and described in U. S. patents to Wales #794,205, July 11, 1905; and #797,032, August 15, 1905; McFarland #842,232, January 29, 1907; Wales #902,125, October 27, 1908; McFarland #924,264, June 8, 1909; and #1,024,013, April 23, 1912; Hunter & Kuntzler #1,054,554, February 25, 1913; Bickford #1,112,516, October 6, 1914; and Pentecost & Fisher, #1,355,258, October 12, 1920, to which reference is made for a more complete understanding of the Wales mechanisms.

The Wales machine includes a base 965 (Fig. 1) supporting the side frames 967 which embrace a keyboard, an accumulating section and a printer section.

The numeral keys 117 forming a part of the keyboard, are arranged in denominational rows. Levers 116 individually connect the keys 117 with their corresponding stops 115 also arranged in denominational files, in line with the paths of denominational adding racks or drive members 310. A rack detent 221 journaled on a cross shaft 202, overlies each file of stops 115, and projects slightly rearwardly thereof, to arrest the racks 310 during an operation of the machine, when no keys and stops in the denominational files corresponding with the racks, have been operated.

The racks 310 are each pivotally mounted on individual front and rear supporting arms 312 and 311, respectively, the front arms 312 being journaled on a cross shaft 300 and the rear arms 311 on a cross rod 301.

Springs 383 connect the rear supporting arms 311 of the respective racks 310, with a transversely extending restraining and re-

storing bar 205 mounted in fingers 265^m depending from a rock shaft 265 journaled in the side frames 967 and oscillated from the main drive shaft 200 by means, not herein shown, but fully disclosed in the patents 70 above mentioned.

Denominational counters 490 independently journaled on an axle 400 extending transversely of the machine above the adding racks or drive members 310, each have 75 associated therewith a pinion 435 adapted to engage with and disengage from its respective rack 310. Arms 322 pivoted at 952^d to the side frames 967, support the axle 400 with the counters 490 and pinions 435, the counters and their pinions being normally held out of mesh with the racks 310, by means of props 319 pivoted at their upper ends, at 357, to the arms 322, and being slotted at their lower ends to embrace and rest 85 upon the oscillatory counter-engaging and disengaging bar 303 mounted in radius arms 323 journaled on the shaft 300. Links 214 connect the bar 303 with cranks 212 fast on the main drive shaft 200, which is held 90 in its normal position by the usual main restoring springs 285, the bar 303, in consequence, being held at the upper end of its arcuate path of travel.

Depression of the numeral keys 117 in 95 the various denominational rows corresponding with the digits of the amount to be registered on the counters 490, in an adding operation, projects the appropriate stops 115 into the paths of the corresponding denominational racks 310, the projected stops 115 displacing the corresponding rack detents 221, and being releasably held projected by the usual latches 114.

Advancing the main drive shaft 200 on 105 its forward stroke in any suitable manner, against the tension of restoring springs 285, operates the customary and well-known Wales mechanism (not shown) to rock the shaft 265 and the fingers 265^m and withdraw the universal bail 205 from its restraining position in front of the front rack-supporting arms 312, to enable the racks 310 to advance under the tension of their drive springs 383 until they contact 110 with the projected stops 115, or the rack detents 221 in those denominations wherein no stops 115 have been projected.

The main drive shaft 200, on its forward stroke, also rocks cranks 212 to draw the 120 links 214 forwardly and swing the counter-engaging and disengaging bar 303 on its downward arc of travel, thereby relieving the arms 322 of the support afforded by the props 319. Removing the support of the 125 props 319 from the arms 322 would permit the synchronous descent of the axle 400 with its counters 490 to mesh the pinions 435 with the racks 310, were it not for the provision of legs 316 depending from the projecting 130

ends of the axle 400, the legs having feet at their lower ends lying in line with rests 958^a, and adapted to contact with such rests at the outset of the attempted descent of the 5 axle 400, to maintain the counters 490 and their pinions 435 out of mesh with the racks 310 until the latter have completed their advance. Bridle links 321 connected to the legs 316 are slotted to embrace the counter-engaging and disengaging bar 303, which, 10 as it progresses on its downward arcuate path, idly traverses the slots in the bridle links 321 and props 319 until, near the end of the forward stroke of the main drive 15 shaft, the bar 303 contacts with the outer end walls of the slots in the bridle links 321 to trip the legs 316 off of the rests 958^a, whereupon, the axle 400, with its counters 490 and pinions 435, quickly drops to mesh 20 the pinions with the advanced racks 310.

At the end of its forward stroke, the main drive shaft 200 is released to the action of its restoring springs 285, which return the shaft to its normal or home position.

25 The main drive shaft, on such return, through the usual mechanism (not shown) presses the universal restraining and restoring bail 205 against the front arms 312 of the advanced adding racks 310 to return 30 them to normal position, the racks 310 during such return, operating to turn the pinions 435 meshed therewith and the counters 490, to register thereon the amount set up 35 on the keyboard and represented by the depressed keys 117.

At the same time, the counter-engaging and disengaging bar 303 is being returned through cranks 212 and links 214 along its upward arcuate path, the bar idly traversing the slots in the bridle links 321 and props 319 until, near the end of the return stroke of the main drive shaft, and after the racks 310 have been restored to their home positions, the bar 303 contacts with the upper ends of the slots in the props 319 to lift 40 the axle 400 and thereby disengage the pinions 435 from the drive members 310. The legs 316 rise with the axle and as soon as 45 their feet clear the rests 958^a, springs 385^c operate to snap the legs into line with such rests preparatory to the next operation.

50 Suitable means (not shown) also operates automatically to displace the latches 114 and enable the projected stops 115 and depressed keys 117 to restore to normal position.

55 Printing of the amount set up on the keyboard occurs near the end of the forward stroke of the main drive shaft 200, and is provided for as follows:

Converging levers 311^m project rearwardly from the respective rear rack-supporting arms 311 and are connected by links 60 65 315 to the corresponding denominational typecarriers 514, in the heads of which

typecarriers are mounted the types 561 arranged in vertical rows commencing at the upper end with "0" and terminating with "9" at the lower end. The cipher types lie just below the printing line of the platen 70 2094, and the advance of the racks or drive members 310 until they contact with the rack-arresting detents 221, positions the cipher types at the printing line. The racks 310, when advanced until they contact with 75 the "1" key-set stops 115, lift the typecarriers a step farther to position the "1" types at the printing line, and so on. Printing hammers 510, by their impact against spring-retracted firing pins 562^b located in 80 line with the type stems when the types 561 are positioned at the printing line, drive the types against the paper on the platen 2094.

The denominational printing hammers 510 are actuated by springs 580 suitably tensioned just prior to the time of firing, the 85 hammers being reset or cocked by a resetting bail 505^d operated in a manner usual in the Wales machines, on the return stroke of the main drive shaft 200.

A universal latch 518 carried by a shaft 502, normally retains the hammers 510 in cocked position during the forward stroke of the main drive shaft, at which time the cocking bail 505^d is being withdrawn from 90 the paths of the hammers, and in addition, the hammers are locked against operation by individual dogs 511 journaled on a cross rod 504, and held in effective position by springs 581.

95 Trip bars 513 coact with each dog 511, to release the latter, the bars being pressed against the tails of their respective dogs 511, by springs 583, and having lateral ears 513^m extending beneath their respective converging levers 311^m.

100 The levers 311^m when in their normal lowered position, contact with the ears 513^m of the trip bars 513 to retain the latter in their lowered idle positions against the tensions 110 of their springs 583. As the converging levers 311^m swing upwardly due to the advance of the corresponding drive members 310 against the projected stops 115, they release the ears 513^m and the trip bars 513 to 115 the action of their springs 583, which raise the trip bars, causing the upper ends of such bars to contact with the tails of the corresponding individual dogs 511 and rock the dogs to idle position, thereby freeing the corresponding hammers 510 for operation as 120 soon as released by the universal latch 518.

125 As the main drive shaft 200 approaches the end of its forward stroke, it operates mechanism well known in the Wales machine and disclosed in the patents above referred to, to lift the universal latch 518 to idle position, thereby freeing those hammers 510 which have been released by their individual dogs 511, for operation, the re- 130

leased hammers driving the firing pins 562^b against the types 561 positioned at the printing line.

5 Advancement of the racks 310 to position the cipher types at the printing line is not sufficient to enable the trip bars 513 to trip their individual dogs 511, but each dog is provided with the usual cross-over finger to enable the printing of ciphers to the right 10 of the digit of highest value, in the customary manner.

15 The main drive shaft 200 on its return stroke, swings the resetting bail 505^a forwardly, to recock the discharged hammers, which, when restored to set position, enable 20 the universal latch 518 to snap back to effective position to temporarily hold the hammers cocked while the resetting bail is being withdrawn on the next forward stroke 25 of the main drive shaft.

25 The drive members 310, on their return to normal position by the restraining and restoring bar 205, above explained, lower those converging levers 311^m which have been elevated, and, through the links 515, 30 the levers 311^m lower their corresponding type carriers 514 to normal position.

35 The converging levers 311^m on their return, contact with the ears 513^a of the trip bars 513 to withdraw the latter out of contact with the individual dogs 511, which thereupon swing upwardly under the influence of their springs 581, to lock the denominational hammers 510 in cocked position.

40 To print a total of the amounts accumulated on the counters 490 and clear the counters, the operator depresses a total and clearing key 327 releasably connected by a latch 326^c, to the forwardly extending arm of a set lever 317^b fast on the cross shaft 300. A link 315 connects the upwardly extending arm of the set lever 317^b with the leg 316, the set lever and link being duplicated on the opposite side of the machine, 45 so that upon operation of the set levers, the detaining legs 316 are displaced relatively to their rests 958^d, and as a consequence, the counters 490 and their pinions 435 drop 50 into mesh with their drive members 310 at the beginning of the forward stroke of the main drive shaft 200, to enable the drive members to reversely rotate the counters 490 to their zero positions, during the advance of the drive members, as is common 55 in the Wales machines and clearly set forth in the prior patents referred to, so that further explanation is unnecessary. The drive members 310 in this operation are 60 under the control of the counters 490 and position types at the printing line corresponding to the amount registered on the counters, the hammers 510 operating to impress the types on the paper, as explained, 65 to record such total amount.

At the beginning of the return stroke of the main drive shaft in totaling operations, means (not shown) effects the disengagement of the counters 490 and their pinions 435 from the drive members 310 prior to 70 the return of the latter to home position, whereby the counters remain at zero while the drive members return to their normal positions of rest.

75 Depression of a sub-total key 327^b operates the set lever 317^b as does the total and clearing key 327, to trip the detaining legs 316 to enable the counters 490 and their pinions 435 to mesh with the drive members 310 prior to the advance of the latter. As 80 the drive members advance, they reversely rotate the counters to their zero positions, and set the types to represent the amount registered by the counters, which is printed, as usual, near the end of the forward stroke 85 of the main drive shaft.

90 The counters are not disengaged from their drive members, however, until near the end of the return stroke of the main drive shaft, and hence the drive members 95 310, as they restore to normal position, turn the counters to cause them to again register the amount previously displayed thereon.

95 Sometimes it is desired to print a number without registering it on the counters, which operation is effected by preventing the engagement of the counters 490 and pinions 435 with their racks, in a manner well known in the art and disclosed, for example, in patent to McFarland, #1,024,013, dated 100 April 13, 1912.

105 Also, it often happens that the operator wishes to add an amount on the counters 490 without printing the same. Depression of key 526^b (Figs. 2 and 3) projecting through an aperture in the case 1065 of the machine and through a slotted scutcheon plate 1018^d covering such aperture, depresses a short link 419 over which the hollow sleeve of the key 526^b fits.

110 The link 419 is pivotally connected to a key stem 523^b by a slot and pin connection 458. A spring 582 connected to the link 419 and to the pin 458 in the stem 523^b, holds the link at the upper limit of its travel 115 as determined by the slot therein. Depression of the link 419 depresses the key stem 523^b connected at its lower end at 562^c to an arm projecting forwardly from one side of a substantially U-shaped rocking comb 120 524^c having teeth 524^c, and pivotally mounted on a cross rod 506^d, to shift the teeth of the comb into the paths of shoulders 513^b formed on the lower ends of the trip bars 125 513 associated with the individual dogs 511 of the denominational printing hammers 510, and this locks the trip bars 513 against 130 operation.

Obviously, if the trip bars 513 do not rise to displace the individual dogs 511, the lat-

ter remain effective to restrain the hammers 510 from operation, notwithstanding the release of the universal latch 518, and consequently no printing of the amount set up 5 on the keyboard occurs. The detention of the trip bars 513 in idle position has no effect on the operation of the drive members 310, which, during the operation of the main shaft 200 on its forward and return strokes. 10 lift the type bars 514 to position the types at the printing line, register the amount on the counters 490 and return the type bars 514 to their home positions.

Releasing the non-print key 526^b enables 15 the restoring spring 589^b connected to the stem 523^b, to return the non-print comb 524^a to idle position, and restore the key to its normal elevated position.

The foregoing mechanisms are usual in 20 the Wales machine and form no part of the present invention, except in so far as they coact therewith to produce the various results hereinafter explained.

It has been customary, in the Wales machine, to arrange for the printing of various signs to designate non-add, totaling, and sub-totaling operations, and to this end, it is usual to provide a special typecarrier 514^m (Figs. 2 and 3) in which are mounted the 25 non-add sign printing type 561^w, the total sign printing type 561^x, and the sub-total sign printing type 561^y. The non-add type 561^w is usually at the upper end of the typecarrier 514^m, and normally lies opposite the 30 printing line on the platen 2094, as shown in Fig. 2. Depression of a non-add key (not shown) trips the individual hammer-locking dog 511^c, against the tension of its spring 581^c, by means common to the Wales 35 machine, so that upon the withdrawal of the hammer-resetting bail 505^d, and the release of the universal latch 518, a sign printing hammer 517^a, similar to the regular printing hammers 510, will drive its firing 40 pin 562^b against the type stem 561^w to impress the non-add sign type on the paper as an incident to the printing of the non-added amount.

It will be noted that no adjustment of the 45 sign typecarrier 514^m is necessary to position the non-add sign at the printing line, but it is necessary to provide means to adjust the remaining signs relatively to the printing line, as well as to provide means to release 50 the individual dog 511^c from the sign printing hammer 517^a.

Thus, depression of the total key 327 (Fig. 1) for instance, causes a stud 344 mounted on the lower end of the total key 55 stem to wipe along a cam edge 326^m formed on a slide 326^d extending along the base of the machine from front to rear, the rear end of the slide being connected to a crank 1814 fast on a cross shaft 1801. Contact of the 60 wiping stud 344 with the cam edge 326^m

shifts the slide 326^d rearwardly against the tension of a return spring 682^d to rock the shaft 1801, which shaft carries an arm 1814^b. A lifting pin 963 projecting laterally from the arm 1814^b extends beneath the foot 516^m (Figs. 2 and 3) of a special vertically extending trip bar 516^c, the upper end of which is adapted to contact with the tail of the sign printing hammer dog 511^c to disable the dog, so that the hammer 517^a 75 can operate upon the withdrawal of the resetting bail 505^d and the displacement of the universal latch 518. A link 515 carries at its upper end a pin 550^m slidable in a slot 516^p formed intermediate the ends of the trip bar 516^c, the opposite end of the link being connected to the special sign typecarrier 514^m similarly to the regular or denominational typecarriers 514. A spring 581^x, secured at one end to the pin 550^m, normally 80 retains the latter at the lower end of its slot 516^p and also maintains the trip bar 516^c in its lowered idle position with its foot 516^m resting upon the operating pin 963 in the arm 1814^b, the special sign typecarrier 85 being thus returned to its normal lowered position, wherein the non-add sign 561^w is located at the printing line.

Rocking the cross shaft 1801 by the depression of the total key 327, rocks the arm 1814^b to press the pin 963 against the foot 516^m of the trip bar 516^c, lifting the trip bar to displace the individual dog 511^c, that has held the sign printing hammer 517^a against 90 operation, the elevation of the trip bar 516^c operating to bring the lower end wall of the slot 516^p in the trip bar 516^c against the pin 550^m, to lift the link 515 and with it the sign typecarrier 514^m, to position the total 95 sign type 561^x at the printing line. 100

Operation of the main drive shaft 200 releases the hammer 517^a for operation, as heretofore set forth, and near the end of the return stroke of the main drive shaft, the wiper stud 344 (Fig. 1) withdraws from 105 contact with the cam edge 326^m to free the slide 326^d to the action of its restoring spring 682^d. The spring returns the slide 326^d to normal position, thereby oscillating the shaft 1801 and lowering arm 1814^b with 110 its pin 963, to enable the spring 581^x (Figs. 2 and 3) to lower the trip bar 516^c and the sign typecarrier 514^m to their normal positions. The trip bar 516^c by its return, releases the individual dog 511^c to the action 115 of its spring 581^c which restores the dog to locking engagement with the sign type printing hammer 517^a, the latter having been recocked by the bail 505^d during the return stroke of the main drive shaft. 120

Depression of the sub-total key 327^b (Fig. 1) wipes a stud 344^m on the lower end of its keystem, along a cam edge 326^p on the slide 326^d, the cam edge 326^p being of greater extent, or, it may be, of a greater pitch than 125 130

the cam edge 326^m, whereby the slide 326^d is shifted farther than when the total key 327 is depressed, to rock the arm 1814^b through a greater angular distance and cause it to lift the trip bar 516^g (Figs. 2 and 3 and the sign typecarrier 514^m to a higher point, than when these parts are operated by the total key.

The greater travel of the trip bar 516^g simply rocks the individual dog 511^e of the sign printing hammer through a greater angular movement in shifting it to idle position. The farther travel of the sign typecarrier 514^m positions the sub-total sign type 561^z at the printing line. The parts are returned substantially as set forth in connection with the total key.

Means are associated with both the total and sub-total keys to prevent accidental or intentional mismanipulation of the keys, as set forth in the patents to McFarland #842,232, January 29, 1907; and Pentecost & Fisher #1,355,258, October 12, 1920, so that a partial depression of either key followed by an operation of the main drive shaft will result either in automatically completely depressing the key or in restoring it to idle position, and hence the proper sign will be located at the printing line, or an idle operation will take place.

The non-print sign type 561^z is the lowest of the four sign types, and it is necessary to lift the typecarrier 514^m three steps to bring the non-print type to the printing line, and consequently it would also be necessary to impart a similar throw to the trip bar 516^g. But the non-print key 526^b is completely under the control of the operator, and if the key was positively connected with the sign typecarrier 514^m, the partial depression of the key, either accidentally or intentionally, would lift the sign typecarrier partway only, and effect the imprint of a sign other than the correct sign designating a non-print operation.

To reduce the liability of occurrence of such contingency, I preferably arrange suitably timed means controlled by the non-print key 526^b to operate the trip bar 516^g only as the non-print sign type 561^z is brought to the printing line, and the non-print comb 524^a reaches its fully operative position.

To these ends, I provide means to be controlled by the non-print mechanism, other than the arm 1814^b and lifting stud 963, to operate the sign typecarrier 514^m and the trip bar 516^g.

Referring to Figs. 2 and 3, it will be noted that the non-print comb member 524^a carries a rearwardly extending arm 524^x preferably having a concaved upper edge adapted to contact with the convex end of the depending arm of a bell crank 524^m pivotally mounted at 550^p. The forwardly extending

arm of the bell crank 524^m projects beneath the pin 550^m carried by the link 515 which connects the trip bar 516^g and the sign typecarrier 514^m, such pin entering the slot 516^p in the trip bar.

Depressing the non-print key 526^b and its stem 523^b against the tension of its restoring spring 589^b, rocks the non-print comb 524^a and swings the arm 524^x thereof upwardly against the cammed end of the bell crank 524^m lever 524^m to turn the latter. The forwardly extending arm of the bell crank lever 524^m immediately contacts with the pin 550^m and lifts the latter, together with its link 515 and sign typecarrier 514^m, to shift the non-print sign type 561^z towards the printing line on the platen 2094, independently of the trip bar 516^g, the pin 550^m traversing the slot 516^p in the trip bar especially provided for this operation.

The non-print comb 524^a also commences its travel towards its operative position, but does not become immediately effective.

At about the time when the sign type 561^z just above the sign type 561^z, is substantially located at the printing line, the pin 550^m contacts with the upper end of the slot 516^p in the trip bar 516^g and the farther depression of the key 526^b operates through the comb 524^a, arm 524^x, bell crank 524^m and pin 550^m to lift the trip bar 516^g together with the sign typecarrier 514^m, to displace the individual hammer-locking dog 511^e and also to locate the non-print sign 561^z at the printing line, the comb 524^a shifting to its fully effective position.

With the non-print mechanism set, operation of the main drive shaft 200 (Fig. 1) will advance the racks 310, and position the denominational type bars 514 in accordance with the amount set up on the keyboard, but the comb 524^a, by restraining the trip bars 513 against the action of their springs 583, prevents the trip bars from releasing the individual dogs 511 from their denominational hammers 510, and consequently, although the universal hammer latch 518 shifts to idle position no amount will be printed. The non-print sign 561^z, however, will be printed because the hammers 510 will be held in cocked position by their individual dogs 511 to designate that an adding operation without a corresponding printing operation has taken place, the sign printing trip bar 516^g having no shoulder 513^p, and hence the non-print print comb 524^a has no control thereof.

Should the operator intentionally or accidentally fail to fully depress the non-print key 526^b, the non-print comb 524^a will not shift to effective position, the trip bar 516^g will not displace the dog 511^e and an operation of the main drive shaft 200 would be idle if no numeral keys 117 were set, or would effect an adding and printing operation if an amount is set up on the keyboard.

Complete depression of the non-print key 526^b followed by its partial release will merely permit spring 589^b to withdraw the comb 524^a to ineffective position, and spring 5 581^x will draw the trip bar 516^x downwardly to release the dog 511^x for operation, and though the sign typecarrier 514^m will have only partially descended, the sign printing hammer 517^x will be locked by its dog 511^x to 10 prevent the printing of an incorrect sign.

Furthermore, by arranging to delay the action of the trip bar 511^x on the dog 511^x by the lost motion connection comprising the stud 550^m and the slot 516^p, the dog is not 15 displaced to an excessive extent when the non-print sign type 561^x is brought to the printing line.

Changes may be made in the form and arrangement of the several parts set forth 20 without departing from the spirit and scope of the invention.

What I claim as new, is:—

1. The combination with a printing mechanism; means shiftable into and out of effective position to restrain the printing mechanism from operation; and a manually-controlled device for the restraining means; of special sign printing mechanism, including a sign typecarrier adjustable to 25 bring one or another of the sign types to the printing line; a sign printing hammer for said types; means to lock the hammer against operation; and mechanism actuated by the means which restrains the printing 30 mechanism from operation, to disable the hammer-locking means.

2. In a calculating machine, the combination with accumulating and printing mechanisms; and means to variously affect the operation of the accumulating and printing mechanisms, including settable elements; sign printing mechanism, including a sign typecarrier equipped with types, shiftable to bring one or another type to the printing line to designate various conditions under which the machine has been operated; means to set to effective position one or another of the elements which variously affect the normal operation of the accumulating and printing mechanisms, and to adjust the sign typecarrier to bring the appropriate sign type to the printing line; a sign printing hammer; means to lock the hammer against operation; a trip member for the hammer lock; a bell crank lever controlled by one of the settable elements, and a lost motion connection between the sign typecarrier and the trip member for the hammer-locking means, such connection being operable by 50 the lever to cause the trip member to disable the hammer-locking means upon the arrival of the settable element at its effective position.

3. In a calculating machine, the combination with accumulating and printing mech-

isms; and means to restrain the printing mechanism from operation; of special sign printing mechanism, including a sign typecarrier adjustable to bring one or another of the sign types to the printing line; 70 a sign printing hammer; an individual dog to lock the hammer against operation; means operable through varying distances to trip the dog; and means secured to the sign type carrier and having a lost motion connection with the dog-tripping means, and operable by the restraining means for the printing mechanism to shift the sign typecarrier and insure the location of the appropriate sign at the printing line at the time of its actuation of the dog-tripping means. 75

4. The combination with a printing mechanism; and means shiftable into and out of effective position to restrain the printing mechanism from operation; of special sign printing mechanism, including a sign typecarrier adjustable to bring one or another of the sign types to the printing line; a sign printing hammer; an individual dog to lock the hammer against operation; an 80 element operable through varying distances to trip the dog; means secured to the sign typecarrier and having a lost motion connection with the dog-tripping element; and means to shift the restraining means for the printing mechanism to effective position, and as an incident thereto, to adjust the sign typecarrier to bring the appropriate sign to the printing line, and to actuate the dog-tripping element. 85

5. The combination with a denominational printing mechanism; and means shiftable into and out of effective position, to restrain the printing mechanism from operation; of a special sign printing mechanism, including a typecarrier bearing a type to indicate that an operation of the machine has occurred during which the printing mechanism has been restrained against operation; and means controlled by the restraining 100 member to adjust the typecarrier to bring the appropriate type to the printing line. 105

6. The combination with a denominational printing mechanism; and means shiftable into and out of effective position, 110 to restrain the printing mechanism from operation; of a special sign printing mechanism, including a typecarrier bearing a type to indicate that an operation of the machine has occurred during which the printing mechanism has been restrained against operation; a special sign printing hammer to impress the type; a dog to normally lock the hammer against operation; and means controlled by the restraining 120 member to position the typecarrier to bring the special type to the printing line, and to release the dog. 125

7. In a calculating machine, the combination with accumulating and printing mech-

- anisms; settable elements adapted to variously affect the operation of such mechanisms; and means to set such elements; sign printing mechanism to print appropriate 5 signs to designate operations of the machine during which the settable elements have been effective, such sign printing mechanism including a sign typecarrier equipped with differentiating sign printing 10 types, adjustable relatively to the printing line to bring one or another of the types to printing position; a sign printing hammer; locking means to hold the hammer against operation; and a trip member to disable the 15 locking means; of a lost motion connection between the sign typecarrier and trip member to insure the proper positioning of at least one of the signs at the printing line and the location of the settable element in 20 effective position at the time when the trip member becomes effective to disable the locking means.
8. In a calculating machine, the combination with accumulating and printing 25 mechanisms; settable elements adapted to variously affect the operation of such mechanisms; and means to set such elements; of sign printing mechanism to print appropriate signs to designate those operations 30 of the machine during which the settable elements have been effective, such sign printing mechanism including a sign typecarrier equipped with differentiating sign printing types and adjustable by the settable 35 elements relatively to the printing line to bring the appropriate signs to printing position; a sign printing hammer; and locking means to hold the hammer against operation; a trip member to disable the locking 40 means; of a lost motion connection between the sign typecarrier and the trip member to enable at least one of the setting means to shift its settable element to effective position and adjust the typecarrier to 45 bring the proper sign to the printing line, and trip the locking means substantially simultaneously with the arrival of the proper type at the printing line, and the arrival of the settable element in effective 50 position.
9. In a calculating machine, the combination with accumulating and printing mechanisms; settable elements adapted to variously affect the operation of such mechanisms; and means to set such elements; sign printing mechanism to print appropriate 55 signs to designate operations of the machine during which the settable elements have been effective, such sign printing mechanism including a sign typecarrier equipped with differentiating sign printing types, and adjustable relatively to the printing 60 line to bring one or another of the types to printing position; a sign printing hammer; locking means to hold the hammer against 65 operation; and a trip member to disable the locking means; of a link between the sign typecarrier and the trip member; a projection on the link accommodated in a slot in the trip member; and a lever controlled by 70 one of the settable elements to contact with the projection and impart a limited motion to the sign typecarrier independently of the trip member, whereby the effective operation of the trip member occurs substantially 75 simultaneously with the arrival of the proper sign type at the printing line.
10. The combination in a calculating machine, with accumulating and printing mechanisms; and manually-settable means to vary the operation of the accumulating and printing mechanisms, including means shiftable into and out of effective position to restrain the printing mechanism from operation; of a special sign printing mechanism, including a 80 sign typecarrier adjustable relatively to the printing line to bring one or another type to effective position; a sign printing hammer; an individual locking member therefor; a tripping means to disable the locking member; a lost motion connection between the typecarrier and tripping means; means to retain the lost motion connection at one end of its travel relatively to the tripping means; means operable by certain of the manually-settable means and acting upon the tripping means, to shift the tripping means and the sign typecarrier substantially simultaneously 85 to position one or another type at the printing line and release the individual locking member; and means controlled by the printer-restraining means to shift the lost motion connection to the opposite end of its travel relatively to the tripping means, whereby to enable the sign typecarrier to 90 obtain a lead over the tripping means so that the proper type will be located at the printing line substantially simultaneously with the arrival of the printer-restraining and the tripping means in their effective positions.
11. The combination in a calculating machine, with accumulating and printing mechanisms; and manually-settable means to vary the operation of the accumulating and printing mechanisms, including means shiftable into and out of effective position to restrain the printing mechanism from operation; of a special sign printing mechanism, including a typecarrier adjustable relatively to the 95 printing line to bring one or another type to effective position; a sign printing hammer; an individual locking member therefor; a tripping means to disable the locking member; the tripping means having a slot formed therein; a connection between the sign typecarrier and tripping means, including a pin entered in the slot in the tripping means; a spring connected to the pin to normally hold the latter at one end of the slot; means 100
- 110
- 115
- 120
- 125
- 130

actuated by certain of the manually-settable means and operable upon the tripping means, to shift the tripping means and sign typecarrier substantially simultaneously, to 5 position one or another type at the printing line and release the hammer-locking means; and means controlled by the printer-restraining means and operable upon the pin to shift the latter along the slot, relatively to 10 the tripping means, whereby to enable the typecarrier to obtain a lead over the tripping means to position the lowest sign type at the printing line substantially simultaneously with the arrival of the printer- 15 restraining means and the tripping means in their effective positions.

12. In a calculating machine, the combination with accumulating and printing mechanisms; settable elements adapted to vari- 20 ously affect the operation of such mechanisms; sign printing mechanism to print appropriate signs to designate operations of the machine during which such settable elements have been effective, such sign printing

mechanism including a sign type carrier 25 equipped with different sign printing types, adjustable relatively to the printing line to bring one or another of the types to printing position, a sign printing hammer, locking means to hold the hammer in cocked position; and a trip member to disable the locking means; of a lost motion connection between the sign type carrier and the trip member; means to normally hold the connection at one limit of its travel relatively to 30 the trip means; means to permit certain of the settable elements to operate the trip means directly, to shift the latter and the sign type carrier coincidently; and means controlled by another of the settable ele- 35 ments to operate the sign type carrier relatively to the trip means against the tension of the means which holds the connection at one limit of its travel relatively to the trip member, until the relative travel or lost mo- 40 tion between the sign type carrier and trip means is taken up.

JOSEPH C. COFFEE.
